UNITED STATES PATENT OFFICE

LOUIS A. KOCH, JR., OF LOUISVILLE, KENTUCKY

TERMINAL CONNECTION

Application filed December 29, 1931. Serial No. 583,787.

This invention relates to terminal connections and refers more especially to a new and improved terminal connection for establishing electrical contact to the pig tail terminals of neon-tubes. The invention has 5 for its principal object to provide a terminal connection which may be utilized to make a quick detachable connection in devices which are subjected to vibration as in neon-tube signs mounted on motor vehicles.

10 To the accomplishment of the foregoing related ends, said invention, then, consists of the means hereinafter fully described and particularly pointed out in the claim.

15 In said annexed drawing Figure 1 is a plan view of my improved terminal connection in use showing a portion of a neon-tube and terminal;

20 Figure 2, a similar view on an enlarged scale taken on the section line 1—1 of Figure 4;

25 Figure 3, a detail sectional view of the spring contact element and neon-tube terminal taken on line 3—3 of Figure 2; and

30 Figure 4 a vertical sectional view on an enlarged scale taken on line 4—4 of Figure 1.

As stated hereinbefore, the present invention is primarily directed to improvements in terminal connections for use with neon-tubes or other electrical devices employing 35 so-called pig tail terminals and to also provide an improved terminal connection which may satisfactorily withstand vibration, while at the same time providing means which permit the ready detachment of the 40 neon-tube or other device from the terminal connection.

In the accompanying drawing I have illustrated as a preferred embodiment of this invention one end of a neon-tube 10 having 45 projecting therefrom a pig tail terminal 11, the tube being held with respect to a base 12 by means of the usual strap or other mounting device 13. The base 12 in this embodiment consists of a plate of insulated material 50 and in which is mounted adjacent the terminal 11 the present terminal connection device 13'.

55 This terminal connection is extremely simple in construction and provides a yielding

contact element adapted for detachable engagement with the terminal 11 so as to permit the changing of the neon-tubes without disturbing the terminal connection. More specifically my terminal connection comprises a screw 14 having its end projecting beyond the surface of the plate 12 and its head 15 at the opposite side of such plate. A nut 16 is threaded upon the screw 14 to rigidly secure the same to the plate 12 and to provide, as 60 will hereinafter appear, for certain rotary adjustment of said screw. The outer end of such screw 14 is bifurcated as at 17 in which slot is received the end 18 of a spirally coiled leaf spring contact 19. Nuts 20 and 21 are also threaded on the screw 14 at either side of the spring 19 and engage with one or more of the innermost convolutions of such spring to lock its inner end to the screw 14 as best seen in Figure 4. The outer end 22 of the leaf spring contact element 19 projects laterally beyond the screw 14 into the proximity of the terminal 11 and is adapted to engage therewith when the neon-tube 10 is clamped in place. This outer end 22 may be 65 suitably recessed or provided with an indentation 23 into which is received the outer extremity of terminal 11, thus absolutely insuring any sidewise displacement of the spring end 22 with respect to such terminal as might 70 be caused through vibration of the device as when the neon-tube and terminal connection is mounted on a motor vehicle.

As has been mentioned hereinbefore it is also within the purview of this invention to 75 provide for certain rotary adjustment of the screw 14 in order to vary at will the tension of the outer end 22 of the spring contact element with respect to the neon-tube terminal 11. This may be easily accomplished by simply loosening the nut 16 and rotating the screw 14 in the desired direction until such tension on the outer end of this spring is 80 proper and thereafter to tighten the nut 16 upon the plate 12, thus permanently and rigidly holding the several parts in adjusted 85 position. This adjustment of the screw does not interfere with the locked engagement of the nuts 20 and 21 with the inner end 18 of the spring contact.

Means for connecting the electrical conductor 24 to the screw of my terminal connection may consist of a terminal device 25 to which the end 26 of cable 24 is soldered as at 27 and having the hole 28 therethrough to receive the screw 14. This terminal device 25 may be placed upon the screw 14 in any desired position. In the illustrated embodiment I have shown the same placed in contact in the inner end of spring 19 and held in place by means of nut 21.

I claim:

A terminal connection comprising an insulated base, a screw rotatably mounted therein and having its outer end bifurcated, a coiled leaf spring having its inner end received in said bifurcation and its outer end adapted to be engaged under tension with an electric terminal, nuts threaded on said screw at each side of the inner end of the spring to secure the same to said screw, and a third nut threaded to said screw for engagement with the base to lock the screw to the latter, said last nut permitting rotatable adjustment of said screw to vary the tension of the outer end of said spring against a terminal, and said spring constituting at all times a current carrying portion of a circuit in which a terminal engaged thereby may be included.

In testimony whereof I hereunto affix my signature.

LOUIS A. KOCH, JR.
